UNITED STATES PATENT OFFICE.

JOHAN SKINDERVIKEN, OF CHICAGO, ILLINOIS, ASSIGNOR TO SAID JOHAN SKINDERVIKEN, TRUSTEE.

TELEPHONE-TRANSMITTER.

1,275,776.

Specification of Letters Patent. Patented Aug. 13, 1918.

Application filed November 7, 1917. Serial No. 200,676.

To all whom it may concern:

Be it known that I, JOHAN SKINDERVIKEN, a subject of the King of Norway, residing at Chicago, in the county of Cook and State 5 of Illinois, have invented certain new and useful Improvements in Telephone-Transmitters, of which the following is a specification.

The present invention has to do with improvements in telephone transmitters and the like. In the construction of carbon granule transmitters of the flat disk type, use is made of two flat disks electrically insulated from each other except by way of the carbon granules which are inclosed between them. As long as the transmitter stands upright so that the disks stand in a vertical position, the carbon granules by falling into the lower portion of the transmitter will contact the disks, thereby establishing the electrical circuit. If, however, the disks are placed into a horizontal position, the carbon granules will fall away from the upper disk, thereby opening the 15 circuit and destroying the functions of the transmitter. Consequently, the type of this transmitter can only be effectively used where the mechanism of the transmitter is maintained in a more or less constantly fixed 20 direction. This fact is of considerable disadvantage in the use of this type of transmitter in connection with the so-called continental telephones in which the transmitter and receiver are both connected to the ends 25 of a common handle or stem.

One of the objects of the present invention is to provide a transmitter of such form and construction that the carbon granules will always provide an electrical circuit between the two poles of the transmitter no matter what position the transmitter may be placed in. This will not only adapt the transmitter to a wider range of usefulness, but will also make it unnecessary for the 40 user to hold the instrument in a particular position during its use.

Another object of the invention is to accomplish the foregoing result by the use of a transmitter in which the two poles are 45 formed respectively by a concave and convex surface, providing between them a curved or warped space within which the carbon granules or other resistance particles are contained. By the use of this arrangement,

the carbon granules or the like will effect 55 contact between the two pole surfaces no matter what position the transmitter may be placed in.

Other objects and uses of the invention will appear from a detailed description of 60 the same which consists in the features of construction and combinations of parts hereinafter described and claimed.

Referring to the drawing:

Figure 1 shows a side elevation of a transmitter embodying the features of the present invention, a portion of the body of the instrument being cut away so as to better reveal its interior construction;

Fig. 2 is a cross section taken on the line 70 2—2 of Fig. 1, looking in the direction of the arrows;

Fig. 3 is a cross section through a modified construction of instrument embodying the features of the present invention; and

Fig. 4 is a view similar to Fig. 3 through a second modified type of instrument.

Referring first to the construction shown in Figs. 1 and 2, the same embodies a pair of concentric spherical portions provided 80 between them a curved space for the accommodation of the carbon granules. These spherical portions are the inner ball or sphere 4 and the outer spherical shell 5. This outer shell is conveniently formed as a 85 split ball of thin material such as thin aluminum with a copper or gold-plating on its interior surface. The interior ball 4 may be a solid ball of carbon or of metal with gold or other similarly plated surface. The 90 essential point is that the two concentric spheres shall be of conducting material and their adjacent surfaces shall be suitable for contact with the carbon granules which are placed in the space 6 between them. These 95 are the carbon granules 7. It will be seen from an examination of Fig. 2 that by filling the space 6 only partially full of carbon granules, nevertheless these granules will always fall into such a position as to establish 100 electrical contact with both the spherical surfaces. Even if the instrument be turned on its side or up side down, the electrical circuit will nevertheless be maintained unimpaired. The only requirement is that 105 there shall be enough of carbon granules within the space 6 to initially establish the desired electrical circuit, which circuit will

thereafter be maintained no matter into what position the transmitter may be turned.

As a matter of convenience in construction, I have provided a rod 8 of electrically conducting material which extends through a hole in the outer shell 5 and has its inner end rigidly connected to the ball 4. A sleeve of insulating material 9 incases the lower 10 end of the rod 8 and insulates said rod from the shell 5 as well as providing a mechanical connection to said shell so as to establish the desired relative positioning of the ball 4 with respect to the shell 5.

As a further matter of convenience in mechanical construction, I have shown the invention as applied to a transmitter having a mouth piece 10 and a body portion or backing 11. A plate 12 extends across the 20 body or back 11 and carries the mouth piece 10. The shell 5 is located directly opposite to the mouth piece so that the vibrations will be directly transmitted to the shell 5. The rod 8 has its outer end attached to a ring 25 13 which is incased by a rubber gasket or the like 14 which serves to electrically insulate the ring from the case or back of the transmitter. The ring 13 and rod 8 constitute one pole of the transmitter, whereas the 30 shell 5 constitutes the other pole and the other terminal wire should be attached thereto.

In the arrangement shown in Fig. 3, the transmitter is directly connected to the diaphragm 15. This is done by connecting the rod 8 rigidly to the central portion of the diaphragm as by means of the nut 16. The rubber washer or the like 17 surrounds the periphery of the diaphragm and may 40 take the place of the washer 14 of the arrangement shown in Figs. 1 and 2. In the arrangement shown in Fig. 3, the vibrations of the diaphragm will be directly transmitted to the ball or sphere and through the 45 medium of the rod 8.

The arrangement shown in Fig. 3 presents, in some cases, the advantage that the transmitting device therein illustrated can be directly attached or connected to the diaphragm of an existing transmitter without any modification or change whatsoever in the main body portion of the transmitter. The only change necessary is to remove the disk transmitter from the diaphragm 15 and 55 substitute the spherical transmitter herein illustrated.

In the arrangement shown in Fig. 4 the transmitting device comprises an inner conical plug 18 in combination with an outer 60 conical shell or cup 19 providing a conical space between them within which is con-

tained the carbon granules 20. The conical shell or cup 19 has its periphery 21 threaded for the accommodation of a mica or other insulating disk 22 to the central portion of 65 which is attached the conical plug 18. This attachment may be by way of a threaded pin 23 which extends through the diaphragm 24. The inner conical plug constitutes one terminal of the device, and the outer conical 70 shell constitutes the other terminal.

It will be understood that, while as a matter of convenience I have illustrated the principles of my invention as being contained within a transmitter in which the 75 poles are of circular form, still the essential feature is that said poles shall be of concave and convex surface respectively, so that the space contained between them shall be curved or warped, so that the granules will 80 establish electrical contact or connections no matter into what position the transmitter may be turned.

I claim:

1. In a telephone transmitter, the combination with a diaphragm of a pair of concentric electrodes separated from each other to provide therebetween a circular space, granules of electrically conducting material within said space, and a rigid connection 90 from the diaphragm to both of said electrodes, the electrodes being formed on curved surfaces, and the convex portion of one of said surfaces lying opposite to the concave portion of the other surface for the purpose 95 specified.

2. A telephone transmitter comprising a diaphragm and a pair of electrodes in conjunction therewith, a rigid connection from the diaphragm to the electrodes, and granular conducting material between the electrodes, the electrodes having curved surfaces, and the convex surface of one electrode lying opposite to the concave portion of the other electrode for the purpose specified. 100

3. A telephone transmitter comprising, in combination, a diaphragm, a pair of electrodes, rigidly connected thereto, and granular conducting material between the electrodes, the electrodes having complementary 110 curved surfaces, the protruding portion of one surface lying opposite to the receding portion of the other surface, for the purpose specified.

4. A telephone transmitter comprising, in combination, a diaphragm, a pair of electrodes rigidly connected thereto, and granular conducting material between the electrodes, the electrodes being formed on complementary curved surfaces, for the purpose 115 specified.

JOHAN SKINDERVIKEN.
